UNITED STATES PATENT OFFICE

FREDERIC SCHAEFER, OF PITTSBURGH, PENNSYLVANIA

BRAKE HANGER

Application filed August 30, 1930. Serial No. 479,070.

My invention pertains to brake hangers such as are employed for suspending brake beams in the trucks of railway cars and the like, and especially to brake hangers of the 5 **U** type in which two vertical legs have suspension eyes at their upper ends and are connected at their lower ends by a transverse brake-head engaging yoke.

In the manufacture of brake hangers of 10 the **U** type, it has been found economical to make them of uniform cross-sectional area in the legs and yoke, since the hanger can then be formed by bending from a simple bar without the necessity of any upsetting operations 15 other than such as may be required in order to provide sufficient metal for the suspension eyes. However, the difficulty has been experienced that sometimes such hangers would break at the bends, due to the stretching and 20 buckling of the metallic structure by the bending operation. It is the object of my invention to obviate this difficulty whilst at the same time retaining the economical advantages of a brake hanger which is of uniform cross-section in the legs and yoke.

By way of example, two forms of brake hanger constructed in accordance with my invention are described in the following specification and shown in the accompanying drawing, in which:

Fig. 1 is a front view of a hanger having a yoke of circular section;

Fig. 2 is an edge view of one of the corners of the hanger;

Fig. 3 is a section on the line III—III of Fig. 1;

Fig. 4 is a front view of a hanger having a yoke of pear shape in cross section; and

Fig. 5 is a section on the line V—V of Fig. 4.

Referring first to the construction of brake hanger shown in Figs. 1 and 2, it comprises a pair of legs 10 formed at their upper ends with suspension eyes 11, and connected at 45 their lower ends by a yoke 12. In this form, both the legs and yoke are of circular cross section and of the same diameter, the hanger being produced by bending a bar of uniform cross section. At and adjacent its point of juncture with the yoke, each leg is re-formed,

by forging or pressing, to a reduced diameter at the sides thereof adjacent the inside of the hanger, as indicated at 13. The surplus metal is forced outwardly to form a rib 14 extending around the corner. Such rib 55 bulges from the body of the hanger, not only outwardly at the base of the leg but downwardly, as indicated at 15, below the bottom of the yoke. The operation of reforming the hanger thus at the corners requires the exercise of only a relatively light pressure, so that there is no "flash" or other loss of metal.

By the above means additional strength is given to the hanger at the corners amply sufficient to guard against breakage at these 60 points. This result is obtained without the addition of any metal at the corners, and also without the introduction of any sharp changes in cross-sectional shape, which latter, if present, would of themselves afford 65 a reason for breakage. On the other hand, the operation of forging the corners as described is quite economical, and adds little 70 to the cost of the hanger.

My invention may be applied to brake 75 hangers having yokes of other than circular cross section. For instance, in Figs. 4 and 5 there is shown a hanger of the interlocking type, that is, of the type in which the yoke is shaped for interlocking engagement with 80 the brake-head. As in the form shown in Figs. 1-3, the yoke 12a and legs 10a are the same in cross-sectional area, the hanger being produced by bending a rod of uniform cross-section and then subjecting the yoke 12a to 85 a forging operation to reduce it to the desired interlocking shape, such as the pear shape shown. Preferably at the same forging operation, the diameter of the legs 10a is reduced as indicated at 13a, the surplus 90 metal being caused to flow outwardly only to produce the rib 14a extending around the corner of the hanger and merging into the narrow part of the pear-shaped yoke, such 95 rib having a downward bulge 15a as in the preceding, non-interlocking form.

I claim:

1. A **U**-shaped brake hanger having legs and a transverse yoke integrally formed from a rod of uniform cross sectional area, said 100

hanger being formed with a strengthening rib extending outwardly therefrom around each of the corners and merging at their ends into said legs and yoke, and said ribs being materially narrower than the body of the yoke.

2. A U-shaped brake hanger having legs and a transverse yoke integrally formed from a rod of uniform cross sectional area, said legs being reduced towards the inside of the hanger, adjacent the corners, and being extended outwardly to provide strengthening ribs solely at the outsides of such corners, said ribs being materially narrower than the body of the yoke.

3. A U-shaped brake hanger having legs of circular shape in cross section and a transverse yoke, said legs and yoke being integrally formed from a rod of uniform cross sectional area, and said legs being reduced in diameter adjacent the corners, the balance of the material making up the uniform cross section constituting a strengthening rib extending outwardly around the corners of the hanger and merging at their ends into said legs and yoke, and said ribs being materially narrower than the body of the yoke.

4. A U-shaped brake hanger having legs and a transverse yoke integrally formed from a rod of uniform cross sectional area, said hanger being formed with a strengthening rib around each of the corners merging at their ends into said legs and yoke, and producing a bulge which extends downward below the bottom of the yoke, and said ribs being materially narrower than the body of the yoke.

In testimony whereof, I sign my name.
FREDERIC SCHAEFER.
